UNITED STATES PATENT OFFICE.

JOHN C. F. SCHAFER, OF MOUNT PULASKI, ILLINOIS.

CRIB-HOOK.

No. 895,797.

Specification of Letters Patent.

Patented Aug. 11, 1908.

Application filed May 13, 1907. Serial No. 373,305.

To all whom it may concern:

Be it known that I, JOHN C. F. SCHAFER, a citizen of the United States, residing at Mount Pulaski, in the county of Logan and State of Illinois, have invented a certain new and useful Crib-Hook, of which the following is such a full, clear, and exact description as will enable others skilled in the art to which it appertains to make and use my said invention.

This invention relates to means for connecting the boards or the rails of a crib with the studding or vertical posts of the crib so that the boards or rails may be conveniently detached and replaced.

The purpose of this invention is to provide a hook formed from sheet metal and so constructed as to present broad and flat surfaces in contact with the board and so constructed that it may be connected with the studding by a single nail or equivalent connecting device and when in dis-use may be turned and left in such position as not to interfere with the handling of the board or the handling of the contents of the crib.

With these ends in view my invention consists in the novel features of construction and combinations of parts shown in the annexed drawing to which reference is hereby made, and hereinafter particularly described and finally recited in the claims.

Referring to the drawing in which similar reference letters and numerals designate like parts in the several views; Figure 1 is a partial perspective view of a crib equipped with crib-hooks embodying this invention. Fig. 2. is an enlarged detached perspective view of one of the crib-hooks. Fig. 3. is an enlarged isometric projection of a crib-hook in position on a studding and Fig. 4. is an enlarged plan of the blank from which the crib-hook is formed.

The crib-hook A is made of sheet steel and comprises in an integral structure, laterally projecting wings a; fingers a¹ projecting from the wings a; a forwardly projecting member a² and lugs a³ projecting laterally from the member a²; a hole a⁴ to receive a nail a⁵ or equivalent connecting device, connecting the crib-hook with the studding.

The crib-hook is formed from a blank substantially of the form shown in Fig. 4.

The crib-hook may be formed at a single operation by means of a press equipped with suitable dies adapted to separate the mem-

bers a¹ and a³ from each other and bend the members a upward along the dotted lines X and bend the members a³ upward along the dotted lines Y.

In articles of this kind lightness is a desideratum. A large number of hooks are ordinarily used on a single structure and there is great practical advantage in constructing the hooks of sheet metal so that they may have the requisite strength, may have flat bearing surfaces which will not cut into the wood-work of the crib; may not be subject to accidental breakage; may be easily connected with the crib by nails or equivalent connecting devices which are always at hand; may be conveniently packed for transportation and may be so light as to reduce to the minimum the cost of transportation.

In the practical application of the crib-hook to a crib one or more of the central boards B of the crib will be securely nailed to the studding B¹. The lower fixed board B has along its lower edge a series of notches b adjacent to the studding respectively and accommodating the hooks mounted on the studding so that the hooks may turn upward in the notches.

The hooks are connected with the studding by nails a⁵ passing through the holes a⁴ and driven into the studding, and the hooks turn on the nails.

In erecting the crib the corner posts and studding will be erected and secured in the usual manner. The central boards B will then be nailed to the studding. The hooks A will then be connected with the studding. Beginning at the bottom of the crib the hooks A will be placed in a horizontal position projecting beyond the lower board. The lower board will then be placed on top of the fingers a¹ and against the lugs a³. The hooks A next above the board will then be turned downward until the fingers a¹ lie on the upper edge of the board and the face of the board lies against the lug a³ and this will be repeated in like manner until all of the boards below the lower central fixed board B are in place. The boards above the central fixed board B will then be arranged in like manner upon the hooks.

In practice it is usual to remove the upper board before filling the crib and to remove the lower board while removing the contents of the crib.

The arrangement above described admits

of removing either the upper boards or the lower boards as may be most convenient in practice.

Having fully described my invention what 5 I claim as new and desire to secure by Letters Patent is.

1. A sheet metal hook pressed from a blank substantially as described; comprising a body structure, laterally projecting wings integral with the body structure, and laterally projecting lugs adjacent to said wings respectively; said wings and lugs being shaped to form flat bearing surfaces.

2. A sheet metal hook pressed from a blank substantially as described; comprising

a body structure, laterally projecting wing-members integral with the body structure, and laterally projecting lugs integral with the body structure and pressed from the metal of the wing-members, said wing-members and lugs being shaped to form bearing surfaces at right angles to each other. 20

In witness whereof I have hereunto subscribed my name at Mount Pulaski, Illinois, this 27th day of December, 1906.

JOHN C. F. SCHAFER.
